UNITED STATES PATENT OFFICE

JOSEPH V. MAURAIS, OF MUSCATINE, IOWA

POWER-SHAFT CONNECTION FOR INTERNAL-COMBUSTION ENGINES

Application filed October 22, 1929. Serial No. 401,587.

This invention relates to internal combustion engines and is particularly adaptable to the connecting means that transmits power from the piston to the crankshaft.

5 An object of the invention is to provide for using a straight crank shaft for an internal combustion engine, and furthermore, to arrange the power arm connection so that power will be exerted at all times in a direction substantially perpendicular or at a slight angle to the crank shaft thereby increasing the efficiency of the engine.

Further objects of the invention are to provide, in a manner as hereinafter set forth, 15 a device of the character referred to, that is strong, compact and durable, thoroughly reliable for its intended purpose, very simple in its method of assembly, particularly efficient in its operation and comparatively inexpensive to manufacture and install.

With the foregoing and other objects in view, the invention consists in the novel construction, combination and arrangement of parts as will be hereinafter more specifically 25 described and illustrated in the accompanying drawings, wherein is disclosed an embodiment of the invention, but it is to be understood that changes, variations and modifications may be resorted to without departing from the spirit of the claims here- 30 to appended.

In the drawings, wherein like reference characters denote corresponding parts throughout the several views,

35 Figure 1 is a vertical section in detail through a piston illustrating an adaptation therewith of the device in accordance with the present invention.

Figure 2 is a sectional view through the 40 piston illustrating in end elevation an application of the present invention therewith.

Figure 3 is a fragmentary portion in detailed cross section of the crank shaft with the cam arranged thereon.

45 Figure 4 is a top plan view of a fragmen-

tary portion of the internal combustion engine and the guide arm in accordance with the present invention.

In utilizing the connection of the present invention, it is to be understood that the internal combustion engine explodes every revolution and consequently the valves will have to be arranged to provide for firing the engine on every revolution.

It will also be understood that smaller pistons and shorter strokes of the pistons are provided for, thereby utilizing all the power of the explosion.

Referring to the drawings in detail, 5 indicates a straight powershaft which is journaled for rotation in any conventional manner in the crankcase of an external combustion engine, (not shown in the drawings).

A cam 6 of substantially elliptical configuration is provided at its center with an outset sleeve 7 through which the shaft 5 extends. For rigidly securing the cam 6 to the shaft, sleeve 7 is provided with a threaded opening 8 in which is threadably supported a set screw 9, the inner end of which is adapted to be seated in a recess 10 in the shaft 5 provided for that purpose.

The peripheral edge 11 of the cam 6 is of flat contour to provide an outer track. The outer track 11 is elliptical in shape, and at the opposite ends, or along the major axis of the ellipse is considerably sharpened as will be clearly seen from Figure 1 of the drawings. One face of the cam 6 is provided with a recess 12 having an outstanding wall 13 about the perimeter thereof to provide an inner track thereabout. In configuration the inner track 13 is of substantially the same elliptical shape as the outer track 11, but at the opposite ends thereof the walls are curved to a greater radius than the ends of the outer track as will be clearly understood by referring to Figure 1 of the drawings.

A piston of conventional form for internal combustion engines is indicated at 14 and has

a flat top 15 and a hollow skirt portion 16. A wrist pin 17 is coupled diametrically across the interior of the skirt portion 16 to the walls thereof. Circumposed about the wrist pin 17 is a sleeve 18 formed integral on the upper end of the elongated connecting arm 19.

It is to be understood that this piston is arranged for sliding movement in a cylinder of an internal combustion engine, not shown 10 in the drawings. Any number of pistons may be provided in accordance with the present invention and consequently there will be one piston for each cylinder.

A pair of rollers 20, 21 are rotatably mounted 15 on the respective pins 22, 23 that are secured to the lower end of the connecting arm 19. The pins 22, 23 are arranged in spaced vertical position, one above the other, and the lower roller 21 rides on the inner track 20 13 of the cam 6, while the upper roller 20 rides on the outer track 11. The rollers 21 and 20 project laterally on the arm 19.

On the outer free end of the roller 20 there is an enlarged annular shoulder 24 that is 25 adapted to overlap one outer corner of the cam 6. A depending bracket 25 is secured to a portion of the crankcase 26. Secured to the bracket 25 and extending laterally therefrom, is a cylinder projection 27 that 30 merges at its free end in a reduced pin 28.

Circumposed about the projection 27 is a helical coiled spring, 29, one end of which is secured to the casing 26 as at 30, while the laterally projecting end 31 thereof, bears downwardly on the guide arm 32. A leaf spring 33 has one end secured to the casing 26 as at 34, while the free end 35 bears downwardly upon the arms 32.

The guide arm 32 is for the purpose of causing 40 the roller 20 to always contact with the outer periphery of the cam and which coacts with the roller 21 so as to provide end thrust at the bottom of the connecting arm 19. The guide arm 32 merges at its inner end with an 45 intermediate portion of the connecting arm 19. The outer end of the arm 32 is provided with a longitudinal slot 36 in which is seated the pin 28.

The slot 36 provides for allowing the guide 50 arm 32 to move longitudinally during the stroke of the connecting arm 19.

It is to be understood that by describing in detail herein any particular form, structure or arrangement, it is not intended to limit 55 the invention beyond the terms of the several claims, or the requirements of the prior art.

Having thus described my invention, what I claim as new is:

60 1. A power shaft connection comprising in combination, a piston adapted to be operably associated with a cylinder of an internal combustion engine, a straight shaft adapted to be horizontally journalled through the internal combustion engine, a cam having an 65 outset track rigidly coupled to the shaft, a connecting arm having one end connected to the piston, a pair of vertically spaced rollers rotatably coupled to the arm at the lower end thereof, the rollers being engageable with the opposite sides of the

cam having an outset track rigidly coupled to the shaft, a connecting arm having one end connected to the piston, a pair of vertically spaced rollers rotatably coupled to the arm at the lower end thereof, the rollers being engageable with the opposite sides of the 70 track, an angularly disposed guide arm merging at its inner end with an intermediate portion of the connecting arm and provided with a longitudinal slot on its outer end, a stationary bracket, a pin rigidly secured to the bracket and movably seated in said slot, and automatic means bearing on said guide arm to take up play in said connecting arm. 75

2. A power shaft connection comprising in combination, a piston adapted to be operably associated with a cylinder of an internal combustion engine, a straight shaft adapted to be horizontally journalled through the internal combustion engine, a cam having an 80 outset track rigidly coupled to the shaft, a connecting arm having one end connected to the piston, a pair of vertically spaced rollers rotatably coupled to the arm at the lower end thereof, the rollers being engageable with the opposite sides of the track, an angularly disposed guide arm merging at its inner end with an intermediate portion of the connecting arm and provided with a longitudinal slot on its outer end, a stationary bracket, a pin rigidly secured to the bracket and movably seated in said slot, and automatic means bearing on said guide arm to take up play in 85 said connecting arm, and said cam track being elliptical. 90

3. A power shaft connection comprising in combination, a piston adapted to be operably associated with a cylinder of an internal combustion engine, a straight shaft adapted to be horizontally journalled through the internal combustion engine, a cam having an 95 outset track rigidly coupled to the shaft, a connecting arm having one end connected to the piston, a pair of vertically spaced rollers rotatably coupled to the arm at the lower end thereof, the rollers being engageable with the opposite sides of the track, an angularly disposed guide arm merging at its inner end with an intermediate portion of the connecting arm and provided with a longitudinal slot on its outer end, a stationary bracket, a pin rigidly secured to the bracket and movably seated in said slot, and automatic means bearing on said guide arm to take up play in 100 said connecting arm, and said cam track being elliptical. 105

4. A power shaft connection comprising in combination, a piston adapted to be operatively associated with a cylinder of an internal combustion engine, a straight shaft adapted to be horizontally journalled through the internal combustion engine, a cam fixed to 115

5 said shaft and having inner and outer tracks thereon, a connecting arm having one end connected to the piston, a pair of vertically spaced rollers rotatably coupled to the arm at the lower end thereof, the rollers being engageable with the inner and outer tracks, an angularly disposed guide arm provided on said connecting arm, and means acting upon 10 said guide arm for maintaining one of said rollers in engagement with the exterior periphery of said cam upon reciprocation of said piston.

In testimony whereof I affix my signature.
JOSEPH V. MAURAIS.
